STOVE-TOP BURNER AND AIR SHIELD

Forrest S. Bechtold, Long Beach, Calif.

Application June 5, 1944, Serial No. 538,742

2 Claims. (Cl. 126—39)

1

This invention relates generally to improvements in gaseous fuel burners and pertains particularly to an improved burner for domestic cooking stoves or ranges.

In gas cooking stoves of the character at present employed there is disposed beneath an open grate structure upon which the cooking utensils are placed, a group of burner units each of which consists of a head having a series of apertured fingers through which the fuel gas escapes, and a pipe leading from the gas supply pipe to the head, a valve and air supplying means being connected between the pipe and the fuel gas supply line. In addition, individual supports are provided for the burner units and the area around the units is open and consequently dust, dirt and food materials which may escape from the cooking utensils can collect in the lower part of the stove structure beneath the burners with the result that considerable difficulty is experienced in keeping the structure clean.

A principal object of the present invention is to provide a fuel burner or a burner top structure for gas cooking ranges, wherein all of the parts which are at present separate and independent, are incorporated in a single top unit thereby providing a burner top which is solid or unbroken except in the central part of the small area occupied by the burner fingers.

Another object of the invention is to provide an improved gas burner unit with novel means for supplying auxiliary air for admixture with the burning gases at the flame ports.

Still another object of the invention is to provide an improved gas burner structure in which individual burner units are enclosed in a common housing, with means for the controlled admission of air into said housing and discharge of the same adjacent to the flame or gas discharge ports of the burner.

Still another object of the invention is to provide a gas range burner unit or top structure comprising a relatively shallow housing having openings corresponding to a number of burner units to be enclosed in the housing, with each of said openings having therein finger shells designed to enclose or house the burner fingers of a unit, such shells being spaced from the burner unit fingers to permit the passage of air to discharge ports located above the gas discharge ports of the fingers of the burner units.

The invention will be best understood from a consideration of the following detailed description taken in connection with the accompanying drawing forming a part of the specification, with the understanding, however, that the invention is not confined to a strict conformity with the showing of the drawing but may be changed or modified so long as such changes or modifications mark no material departure from

2

the salient features of the invention as expressed in appended claims.

In the drawing:

Figure 1 is a view in plan of a two burner gaseous stove unit, constructed in accordance with the present invention, portions being broken away.

Figure 2 is a view in side elevation of an end of a top of a stove showing the unit in position.

Figure 3 is a sectional view taken on the line 3—3 of Figure 1.

Figure 4 is a horizontal section taken on the line 4—4 of Figure 3.

Figure 5 is a horizontal section through the front end wall of the housing and the adjacent ends of the gas conduits, showing the air controlled valves.

Figure 6 is a sectional view on an enlarged scale taken on the line 6—6 of Figure 3.

Referring now more particularly to the drawing numeral 10 generally designates a conventional gas range structure, the working top portion of which is designated 11.

In ranges of the type at present manufactured, when the burners are uncovered for use such burners are supported in a well or chamber which is covered merely by an open grate upon which the cooking utensils are placed.

In accordance with the present invention the major portion of the working top of the range is closed and the only openings leading through the top to the under side are at the centers of the burner units.

A two-burner unit, constructed in accordance with the present invention, is shown in detail in Figure 3 and is generally designated U and comprises a relatively flat housing consisting of a top wall 12 having the side or edge walls 13 and the front and back walls 14 and 15 respectively. The lower part of the housing or shell is closed by the bottom wall or plate 16 which may be removably secured to the edges of the walls 13, 14 and 15 or may be welded thereto after the structure has been assembled, as may be desired.

The housing top wall 12 is provided with the two-burner openings 17 into which extend as integral parts of the wall 12 the burner finger shells 18. These shells are alternately long and short so that in a construction having six burner fingers and six finger shells, three of the shells will be long and extend near to the center of the opening while the other three shells which are in alternate relation with the long shells, will be shorter as shown.

The material of the wall 12 is pressed or shaped at the periphery of each opening 17 and in the portions making up the finger shells 18, to provide the opening defining wall 19 and the shell defining wall 20. The edges of these walls 19

and 20 extend down to and have contact with the bottom plate 16.

The material of the longer finger shells is pressed upwardly to form the longitudinally extending utensil rests 21 and one side wall 20 of each finger shell, and the end of such wall near the center of the opening, is provided with a longitudinally extending series of openings 22, the openings being in corresponding sides of the series of finger shells so that the series of openings of one shell is directed toward an unapertured or blank wall 20 of an adjacent shell.

Within the housing are disposed the two burners, each of which is generally designated 23. Each of these burners comprises the usual hollow ring 24 from the inner side of which extends the burner fingers 25 which correspond in number with the shells 18. Connected with each ring 24 is the conduit or tube 26 which extends to the wall 14 of the housing where it is secured so that its open end covers the air admission openings 27 formed in the wall 14, as well as the fuel gas injector opening 28.

Interposed between the secured end of the conduit 26 and the front wall 14 of the housing is a shiftable air admission control plate or valve plate 29 which has apertures 30 which may be moved into registry with the apertures 27 for the full admission of air into the conduit 26 or may be shifted to a position where a portion of the plate 29 closes the apertures 27 or partially closes the same as may be desired.

In the construction here shown the air control valve plate 29 is slidably held in position by the securing elements 31 which are employed for securing the end of the conduit to the front wall 14 but obviously any other suitable means may be employed for regulating the air supply through the conduit for admixture with the injected fuel gas to form a combustible mixture.

The plate 29 is also provided with an opening 32 which is designed to coat with the opening 28 so that the nozzle 33 leading from the gas valve 34, may be directed into the adjacent end of the conduit 26. The valve 34 is of the standard type commonly used in gas stoves and is secured to and receives the fuel gas from the supply pipe or manifold 35.

Each of the burner fingers 25 is provided along one side and round the tip with the fuel gas discharge ports 36, which ports equal in number the openings 22. These ports 36 may be formed in short nozzle-like extensions 37 each of which fit into the lower part of an opening 22. By making each of the gas discharge ports 36 of a height less than the height of the opening 22 through which it discharges, it will be seen that there is provided above each gas discharge port, an air discharge port 38. The shells 18 are slightly larger or greater than the fingers which they enclose and consequently there is provided between each shell and finger, an air passageway 39 leading from the interior of the housing.

The front edge wall 14 is provided between the gas valves with air admission openings 40 whereby air may freely enter the housing and flow through each burner finger shell for discharge through the air discharge ports 38.

While in the description and illustration of the invention reference has been made to a housing or casing enclosing two-burner units it is to be understood that the invention is not to be limited to this number of units in a housing as it will be readily obvious that the housing may enclose one unit only or it may enclose more than two.

Also it will be readily apparent that while the air admission opening has been illustrated and defined as being in the front edge wall 14 of the housing, such opening may be placed in any other wall as may be found desirable.

From the foregoing it will be readily apparent that a stove top constructed in accordance with the present invention may be more easily kept clean than those stove tops wherein the burner units are disposed beneath open gratings and also that with the unit structure here described supplemental air will be supplied to the gas jets for admixture with the gas as it issues from the discharge ports, whereby to improve the combustion.

I claim:

1. In a burner for gas stoves comprising a hollow flat housing designed to form a part of the top of the stove structure and having top, bottom and surrounding side walls, means for admitting air to said housing, an aperture through the top wall of said housing, a hollow gas ring surrounding said aperture and enclosed by said housing, the ring being spaced from the housing top and side walls, means for admitting gas to said gas ring, hollow fingers projecting from said gas ring radially inwardly of the aperture, each hollow finger having gas exit ports in one side wall extending to the aperture, hollow finger shields projecting from said housing radially inwardly of the aperture and completely encasing the hollow fingers but spaced vertically therefrom to form an air passageway, and air exit ports in said hollow finger shields adjacent to said gas exit ports.

2. In a burner unit for a gas stove comprising a hollow flat housing designed to form a part of the top of the stove structure and having top, bottom and surrounding side walls, means for admitting air to said housing, an aperture through the top wall of said housing, a hollow gas ring surrounding said aperture and enclosed by said housing, the ring being spaced from the housing top and side walls, means for admitting gas to the gas ring, hollow fingers projecting from said gas ring radially inwardly of the aperture, gas exit ports in one side wall of each of said hollow fingers extending to the aperture, hollow finger shields projecting from said housing radially inwardly of the aperture each completely encasing a hollow finger but spaced vertically therefrom to form an air passageway, air exit ports in the side walls of said hollow finger shields, said air exit ports in the finger shields being vertically aligned with and closely adjacent to the gas exit ports in the hollow fingers.

FORREST S. BECHTOLD.
